TOILET TISSUE STORAGE AND DISPENSER

Charles M. Clelland, 1923 Seminole St., Kalamazoo Township, Kalamazoo County, Mich., and Lewis C. Aldrich, Jr., 121 W. Kelsy St., Three Rivers, Mich.

Filed Oct. 9, 1961, Ser. No. 143,907

6 Claims. (Cl. 242—55.3)

This invention relates to an improved toilet tissue storing and dispensing device and, more particularly, relates to a toilet tissue storing and dispensing device which includes means for storing a plurality of rolls of toilet tissue and which is provided with mechanism for moving a roll into dispensing position when a previously used roll has been consumed.

The conventional toilet tissue dispenser comprises a single roller or spindle for supporting a single roll of toilet tissue. When this is used up, the core of the roll is removed and a fresh roll is inserted in its place. Thus, it is necessary to obtain a fresh roll from a storage place and this is inconvenient and awkward.

This problem has been recognized heretofore and a number of toilet tissue dispensers having arrangements for storing rolls therein have been suggested heretofore. These dispensing devices, however, have not been completely satisfactory and they have not achieved substantial commercial acceptance. Particularly, the prior storing and dispensing devices have usually stacked the rolls in a vertical row. Thus, the dispensing device is vertically elongated and has a somewhat unsightly appearance. Further, the prior devices have been expensive and difficult to use.

Accordingly, it is an object of this invention to provide an improved toilet tissue storing and dispensing device which includes means for storing a plurality of rolls of toilet tissue and means for moving a fresh roll into dispensing position when the previously used roll has been consumed.

It is a further object of this invention to provide an improved device, as aforesaid, in which at least some of the rolls in storage are horizontally spaced from the roll in use and mechanism is provided to move such stored rolls horizontally into the dispensing position.

It is a further object of this invention to provide an improved device, as aforesaid, which is compact and which has an attractive appearance.

It is a further object of this invention to provide an improved dispenser, as aforesaid, which has a minimum of working parts, which is inexpensive to manufacture and which can be operated easily and conveniently.

Other objects and advantages of this invention will become apparent to persons acquainted with equipment of this type upon reading the following disclosure and examining the accompanying drawings.

In the drawings:

FIGURE 1 is a front elevational view of the toilet tissue storing and dispensing device embodying the invention.

FIGURE 2 is a sectional view taken along the line II—II of FIGURE 1.

FIGURE 3 is a sectional view taken along the line III—III of FIGURE 2.

FIGURE 4 is a sectional view taken along the line IV—IV in FIGURE 3.

FIGURE 5 is a sectional view taken along the line V—V in FIGURE 3.

The toilet tissue storage and dispensing device 10 embodying the invention includes a substantially cup-shaped casing 11 and a decorative front plate 12. The front plate 12 is substantially rectangular and it has a substantially rectangular cut-away part adjacent the lower, right hand corner thereof defining an opening 13. The roll R

2

of toilet tissue in dispensing position is accessible through the opening 13.

The casing 11 is mounted, here by being recessed within an appropriate opening 15, in the wall W on which the device 10 is mounted. The casing has a back wall 16 which is connected by arcuate portions 17 and 18 to the top and bottom walls 19 and 21, respectively. The casing 11 also has end walls 22 and 23. The walls 19, 21, 22 and 23 have reversely curved flanges 24 at their outer ends, the free edges of said flanges being adapted to engage the wall W on which the device 10 is mounted. The flanges 24 are formed to provide shoulders 26. The front plate 12 rests against the shoulders 26 and is secured thereto by suitable fastening means, such as screws 27. The back wall of the casing is secured to the wall W by suitable fastening means, such as screws 28.

The rightward end wall 22 has an offset portion 31 adjacent the lower end thereof. The offset portion 31 of the wall 22 has a central, leftwardly projecting boss 32 and said boss has a pilot recess 33 in the center thereof.

The leftward end wall 23 has a leftwardly projecting, stepped, offset portion 36 which includes an axially inner part 37 and an axially outer part 38. A spindle support 41 is secured to the internal surface of the part 38 by screws 42. The support 41 includes a tubular center post 43 which is axially aligned with the pilot recess 33.

A tubular, stationary spindle 44 is sleeved over and is affixed to the post 43 and extends axially therefrom toward the recess 33 substantially as far as the leftward edge 30 of the opening 13 in the front plate 12.

The spindle support 41 also has a circular, stepped, axially extending flange 46 which comprises a radially inner part 47 and a radially outer part 48. The spindle support 41 also has re-enforcing ribs 49 extending from 35 the outer edge of outer part 48 toward the post 43, the ribs defining a frusto-conical recess 51.

A tubular, sliding spindle 56 is coaxial with and is telescopically mounted on the stationary spindle 44. The sliding spindle 56 has a frusto-conical flange 57 at its leftward end for purposes appearing hereinafter. The rightward end of the sliding spindle 56 is slidably receivable in the pilot recess 33. The end wall 58 of spindle 56 has an offset central portion 59.

45 A coil spring 61 is disposed within the central openings in the stationary spindle 44 and the sliding spindle 56 and one of its ends abuts against the end of post 43. The other end of said spring 61 abuts against the wall 58 and surrounds the offset portion 59. The spring 61 is under compression and, thus, it normally holds the spindles 44 and 56 in their extended positions with respect to each other, as shown in FIGURE 3, wherein the spindle 56 extends across the opening 13 and is piloted in the recess 33.

55 A handle 63 is disposed in front of the casing 11 and is normally disposed adjacent the lower edge of the opening 13 in the front plate 12. The handle 63 is connected by an arm 64 to a pivotally mounted actuating and support member 66. The member 66 is an elongated rod having a central portion 67 extending crosswise of the casing 11 60 parallel with the spindles 44 and 56 from adjacent one end wall 22 to adjacent the other end wall 23. At its rightward end, the member 66 has a transversely extending portion 68 which is disposed within the offset portion 31. The portion 68 is bent to form a ring 69 which encircles 65 and slidably engages the periphery of the boss 32. At its leftward end, the member 66 has a further transversely extending portion 71 which is bent at its inner end to form a ring 72 which encircles and slidably engages the periphery of the radially outer part 48 of the flange 46. The parts are so arranged that the central portion 67 of member 66 can be moved from the position shown in FIGURE

2 to a point adjacent the back wall 16 of the casing 11 by lifting the handle 63.

A further rod 76 is affixed to and extends leftwardly from the ring 72 of member 66. A pulley 77 is rotatably supported on rod 76 and it is located in the axially inner offset part 38 of the wall 23 adjacent the radially inner part 47 of flange 46. Thus, the pulley 77 moves around the part 47 of flange 46 when the member 66 is moved by operation of the handle 63.

As shown in FIGURE 4, a cord 81 is anchored at one end thereof to the casing 11 by being passed through an opening 82 in the wall of the lower offset part 38. The cord is anchored thereto in any suitable fashion, here by being knotted. The cord 81 is passed around a portion of the periphery of the pulley 77 and thence passes through an arcuate opening 80 in the support 41 into the central opening in the post 43. The cord 81 then passes through the central openings in the spindles 44 and 56, through an opening 83 in the offset portion 59 of the end wall 58 of spindle 56. This end of the cord 81 is secured, as by knotting, in the space between the offset portion 59 and the opposing wall of recess 33.

Operation

To load the device 10, the handle 63 is moved to its uppermost position adjacent the upper edge of opening 13. This moves the central portion 67 of member 66 to a position adjacent the back wall 16 of the casing. This movement of the member 66 also effects movement of the sliding spindle 56 leftwardly so that it is fully telescoped over the stationary spindle 44. Thus, when the handle 63 is raised, the member 66 is pivoted toward the back wall and this effects corresponding movement of the pulley 77, which moves same away from the opening 80. This, therefore, pulls the cord 81 through said opening and thereby effects movement of the sliding spindle 56 leftwardly against the contrary urging of the spring 61.

When the spindle 56 is in its leftward position, the first roll R₁ of toilet tissue is inserted through opening 13 and placed around the spindles 44 and 56 and is moved leftwardly therealong to a position in the lower, left-hand corner of the casing. The second roll R₂ is inserted into the casing and is moved into the upper lefthand corner thereof and is placed on the roll R₁. The third roll R₃ is then inserted into the casing and is moved into the upper righthand corner thereof. The roll R₃ is held in this position by hand, ordinarily the hand which the operator is using to hold the handle 63 in its upper position. The fourth roll R₄ is then inserted into the lower righthand corner of the casing and the handle 63 is permitted to move to its lower position so that the sliding spindle is extended through the roll R₄ and is received within the recess 33. This movement of the handle is assisted by the spring 61. The chamfer on the rightward edge (FIGURE 3) of the flange 57 permits the flange to slide past the leftward end of the core in the roll R₁, when the roll R₄ is in the lower righthand corner of the casing. However, such chamfer is designed so that the flange 57 will move the roll R₁ rightwardly when the roll R₄ is removed from the lower righthand corner of the cabinet.

At some point during the downward movement of handle 63 the central portion 67 of member 66 lifts the rolls R₂ and R₃ off the rolls R₁ and R₄. Thus, in the fully loaded condition of the device 10, the first and fourth rolls R₁ and R₄ are supported upon the bottom wall 21 and encircle the spindles 44 and 56, respectively, and the rolls R₂ and R₃ rest on the central portion 67 of the member 66 above the rolls R₁ and R₄, respectively. The fourth roll R₄ is immediately available for dispensing toilet tissue through the opening 13. After part of the tissue is used from roll R₄, this roll is then supported upon the spindles 56, which is fully capable of such support.

When the roll R₄ is used up, the handle 63 is raised to effect leftward movement of the sliding spindle 56. The central portion 67 of member 66 moves toward the back-wall 16 and ceases to support the rolls R₂ and R₃. When

the handle has been moved to an appropriate point, the core of the roll R₄ will drop out through the opening 13. Roll R₃ then drops into the lower righthand corner of the device. By moving the handle downwardly, the sliding spindle 56 is moved rightwardly and through the core of roll R₃ so that said roll is thereafter supported in dispensing position. It is not necessary to raise the handle 63 to its uppermost position to effect this change of rolls and, thus, the flange 57 does not clear the end of the roll R₁. However, even if the handle 63 is raised to its uppermost position, the fact that the flange engages the ends of the roll R₁ causes no serious difficulties in the operation of the device because of the chamfer on the flange 57, as discussed above.

When roll R₃ is used up, the handle 63 is raised to its uppermost position. This retracts the spindle 56 so that the core of roll R₃ drops out through the dispensing opening 13 and it also moves flange 57 past the leftward end of the roll R₁ so that the leftward end of roll R₁ is engaged by said flange. Thus, when the handle is again moved to its lowermost position, the flange 57 will hold the roll R₁ with respect to the spindle 56 and said roll R₁ will move rightwardly therewith into dispensing position. It is to be noted that during at least the initial part of the rightward movement of roll R₁, the roll R₂ will be resting thereon and will move rightwardly therewith. However, at some point during its travel as a result of downward movement of handle 64, the central portion 67 of member 66 will lift the roll R₂ off the roll R₁ and said roll R₁ will complete its rightward movement into the dispensing position alone.

When the roll R₁ is used up, the handle 63 is raised as before so that the core of said roll drops out through the opening 13. The roll R₂, having previously been moved rightwardly with roll R₁, will now be in a position where it can move downwardly into a position in the lower righthand corner of the casing. The handle 63 is then moved to its lower position and thereby the sliding spindle 56 is extended through the roll R₂ to hold same in dispensing position. A horizontal guide rail, which is indicated by broken lines at 84 in FIGURE 2, may be provided if needed in the leftward side of the rear wall 83 to prevent downward movement of the roll R₂ when it is not in the upper righthand corner of the cabinet.

Although a particular preferred embodiment of the invention has been disclosed hereinabove for illustrative purposes, it will be understood that variations or modifications thereof, which lie within the scope of the appended claims are fully contemplated.

What is claimed is:

1. A toilet tissue storing and dispensing device, comprising: a casing; elongated spindle means supported within said casing, the spindle means being sufficiently long to hold a plurality of rolls of toilet tissue within said casing with the cores of said rolls being longitudinally aligned, said spindle means including a plurality of spindles which are movable into telescoping relation, each spindle being adapted to hold a roll of toilet tissue; means for moving said spindles into telescoping relation; means for moving a roll from one spindle to another as they are thus telescoped, and means for moving said spindles into their extended positions with respect to each other.

2. A device according to claim 1 wherein said spindles are tubular and one spindle is sleeved over the other; resilient means normally urging said spindles into their extended position with respect to each other; and manually operable means for moving said spindles into their telescoped relation.

3. A toilet tissue storing and dispensing device, comprising: a covered casing having a dispensing opening, said casing defining an enclosure for holding toilet tissue rolls in horizontally and vertically arranged rows; a pair of horizontally arranged, tubular spindles, one of said spindles normally extending horizontally across said dis-

pensing opening and being mounted for telescoping over the other spindle; means projecting from said one spindle for engaging a toilet tissue roll on the other spindle when said spindles are telescoped and for moving same off said other spindle onto said one spindle; means for moving said spindles between their telescoped and extended positions and means for supporting the rolls above those on said spindles in vertically spaced relationship with respect thereto.

4. A device according to claim 3 wherein said other spindle is stationarily mounted on said casing; a spring for urging said spindles into their extended position with respect to each other; an elongated flexible element for moving said spindles into their telescoped position; and a manually operable handle for effecting operation of said element.

5. A device according to claim 3 wherein said means for moving said spindles and said supporting means includes a pivotally mounted member which is movable

between a position wherein it is between the rolls mounted on the spindles and the rolls thereabove and a position wherein it is located sidewardly of the rolls; and a manually operable handle connected for moving said member between its positions.

6. A device according to claim 5 wherein said means for moving said spindles includes a cord anchored at one end to said casing and anchored at the other end to said one spindle; a pulley mounted on said member; said cord at least partially encircling said pulley whereby movement of said member effects movement of cord longitudinally of the spindles.
